UNITED STATES PATENT OFFICE.

LOUIS H. MACOMBER, OF MONTEVIDEO, MINNESOTA, ASSIGNOR TO HIMSELF
AND ARCHIBALD M. ELLITHORP, OF SAME PLACE.

FLYING TARGET.

SPECIFICATION forming part of Letters Patent No. 326,664, dated September 22, 1885.

Application filed February 5, 1885. (Model.)

To all whom it may concern:

Be it known that I, LOUIS H. MACOMBER, of Montevideo, in the county of Chippewa and State of Minnesota, have invented a new and Improved Flying Target, of which the following is a full, clear, and exact description.

The object of my invention is to provide a new and improved flying target which drops as soon as it is struck by shot, a ball, or other missile, does not break, and can be folded very compactly.

The invention consists of the combinations of parts and their construction, substantially as hereinafter fully set forth, and pointed out in the claims.

Reference is to be had to the accompanying drawings, forming part of this specification, in which similar letters of reference indicate corresponding parts in all the figures.

Figure 1 is a longitudinal sectional elevation of my improved flying target closed. Fig. 2 is a face view of the same opened. Figs. 3, 4, 5, 6, and 7 are side views of modifications of the same. Fig. 8 is a cross-sectional view of another modification, the wing being held against the target. Fig. 9 is a view in side elevation thereof opened.

The flat cone-shaped target A, made of sheet metal, compressed paper, wood pulp, or other non-breakable material, is provided with a conical wing, B, having a tongue, C, which is hinged by means of a ring, D, to the rim of the target A, the said wing fitting closely and snugly against the inner side of target, and is held in place by means of cement, E, or a suitable catch, F, as shown in Figs. 4 and 5. The target is thrown in the usual manner, and when it is struck by the shot or other missile the wing B is released from the target at one of its ends, and is thrown out by the centrifugal force. The weight of the said wing acting on the rim of the target, and the resistance offered by the wing and target, cause the target to drop as soon as it is struck. The wing is held to the inner side of the target by the cement or catch until the target receives a jar or shock, as it does when struck by shot, &c.

In the construction shown in Figs. 3 and 4

the target A and the wing B are formed of 50 parts of a hollow ball.

In Fig. 3 the smaller wing rests on the outer convex surface of the target, and in Fig. 4 the concave sides face each other, the target and wing being of the same size and held together 55 at the edges.

In Fig. 5 the target and wing are of the same size, and each consists of a quarter or like part of a hollow ball hinged together at the angles.

In Fig. 6 the target and wing are of the same size, and each is formed of half a hollow ball.

In Fig. 7 the target consists of part of a hollow ball, and the wing consists of a circular plate adapted to close the opening of the target.

In the modification shown in Figs. 8 and 9 an annular groove, T, is formed in the cup-shaped target by pressing a part of the material inward, thereby forming an annular ridge on the inner surface of the target. The wing B is provided with a notch or slot, W, which gives the wing spring-tension. To hold the wing on the inside of the target it is swung 75 up against the under side and pressed together. When it expands, it catches on the bead or ridge formed on the inside of the target, and is thus held in place as well as if it were held by cement or a spring-catch. The 80 action is the same in all cases.

Glass or clay balls or targets are often struck by shot, but not broken, and are counted as a miss, and against the marksman, whereas they should be counted for him. My improved 85 target drops as soon as it is struck, and mistakes are impossible.

As the targets cannot be broken, they can be used a number of times, and there is no danger of breaking them during transportation. They occupy less space than other targets, as they need not be packed in straw, hay, &c.

Having thus described my invention, what I claim as new, and desire to secure by Letters 95 Patent, is—

1. The combination, with a cup-shaped or conical target having an annular bead or pro-

jection on its inner surface, of a wing hinged on the said target and adapted to catch on the said bead or projection, substantially as herein shown and described.

5 2. The combination, with a cup-shaped or conical target having an annular bead or projection on its inner surface, of a wing hinged on the target and provided with a notch or recess to give the wing spring-tension, substantially as herein shown and described.

3. The combination, with the target A, of the wing B and the ring D, together with a cement for temporarily holding the wing at one edge to the target, substantially as and for the purposes set forth.

LOUIS H. MACOMBER.
